UNITED STATES PATENT OFFICE.

ANDREW L. STAFFORD, OF BAR HARBOR, MAINE.

DESIGN FOR A VEHICLE-BODY.

SPECIFICATION forming part of Design No. 25,759, dated July 7, 1896.

Application filed May 19, 1896. Serial No. 592,225. Term of patent 7 years.

To all whom it may concern:

Be it known that I, ANDREW L. STAFFORD, a citizen of the United States, residing at Bar Harbor, in the county of Hancock and State of Maine, have invented a new and original Design for a Vehicle-Body, of which the following is a specification.

This invention relates to a new and original design for a vehicle-body; and it has for its object to provide a design of this character that shall be both useful and ornamental.

The leading feature of the design resides in a vehicle-body essentially comprising an elongated horizontal platform or board, a plurality of passenger-seats arranged transversely of the platform at regularly-spaced distances apart and having wide rectangularly-shaped upright backs, and at opposite ends depending quadrangular pedestal-panels joined to the platform at the opposite top edges thereof, an enlarged seat-boxing arranged on the front end of the platform and provided with an inclined front end-board and opposite vertical side pieces having upright extensions, an elevated driver's seat supported on said upright extensions and disposed in a plane above the plane of the top edges of the backs of the passenger-seats, a rear boxing arranged on the rear end of the platform and supporting thereon opposite quadrangular pedestal-panels, and a hornman's seat arranged on said panels and disposed in a horizontal plane approximately in a line with the plane of the top edges of the backs of the passenger-seats.

In the drawing, the figure is a perspective view of a vehicle-body embodying the herein-described design.

Referring to the drawing, the numeral 1 designates an elongated horizontal platform or board, transversely of which is arranged a

plurality of passenger-seats 2, and which platform or board is supported for travel over the ground on the running-gear 3. The transverse passenger-seats 2 are of the same width 45 as the platform 1, and are provided with wide rectangularly-shaped upright cushioned backs 4, and at opposite ends with quadrangular pedestal-panels 5, which are joined to the platform at the opposite top edges thereof. 50

An enlarged seat-boxing 6 is arranged on the front end of the platform and is provided with an inclined front end-board 7 and opposite vertical side pieces 8. The opposite vertical side pieces 8 are provided with upright 55 extensions 9 and rectangular slatted windows 10, and at the upper edge of the inclined front end-board 7, and at an obtuse angle thereto, is supported the inclined foot-board 11, in front of the driver's seat 12. The driver's seat 12 is arranged on the upright extensions 9 of the side pieces 8, and is disposed in a plane above the plane of the top edges of the seat-backs 4.

A rear boxing 13 is arranged on the rear 65 end of the platform and supports opposite quadrangular pedestal-panels 14, on which panels is located a hornman's seat 15, having an upright back 16 and disposed in a plane approximately in a line with the plane of the 70 top edges of the seat-backs 4.

What I claim is—

The design for a vehicle-body herein shown and described.

In testimony that I claim the foregoing as 75 my own I have hereto affixed my signature in the presence of two witnesses.

ANDREW L. STAFFORD.
